UNITED STATES PATENT OFFICE

117,513

DESIGN FOR A WIND CHARGING UNIT

John R. Albers, Sioux City, Iowa

Application April 15, 1938, Serial No. 76,537

Term of patent 7 years

To all whom it may concern:

Be it known that I, John R. Albers, a citizen of the United States residing at Sioux City, in the county of Woodbury and State of Iowa, have invented a certain new, original, and ornamental Design for a Wind Charging Unit, of which the following is a specification, reference being had to the accompanying drawings, forming a part thereof, in which:

Figure 1 is a side elevation of the wind charging unit showing my new design,

Figure 2 is a plan view of the same,

Figure 3 is a sectional view taken substantially along the line 3—3 of Figure 1 the supporting standard socket and rudder being omitted and

Figure 4 is an enlarged view of that portion of the unit shown in solid lines in Figures 1 and 2, with the motor casing omitted.

The dominant features of my design are shown in solid lines in the drawings.

I claim:

The ornamental design for a wind charging unit, as shown and described.

JOHN R. ALBERS.
